UNITED STATES PATENT OFFICE.

BENJAMIN B. LACY, OF HOUSTON, TEXAS, ASSIGNOR, BY MESNE ASSIGNMENTS,
TO ANDERSON-LACY ELECTRIC HEADLIGHT COMPANY, A CORPORATION OF
TEXAS.

ARC-LAMP HEADLIGHT.

No. 911,409.

Specification of Letters Patent.

Patented Feb. 2, 1909.

Application filed September 24, 1907. Serial No. 394,843.

To all whom it may concern:

Be it known that I, BENJAMIN B. LACY, a citizen of the United States, residing at Houston, in the county of Harris and State of Texas, have invented certain new and useful Improvements in Arc-Lamp Headlights, of which the following is a specification.

My invention relates to arc lamps designed for use in head lights for locomotives, automobiles and vessels of various kinds, and has for its object to produce a construction which will maintain a steady and unfailing light, notwithstanding the jolting and vibration to which it may be subjected in use, and will maintain the luminous arc in the focal point of the reflector during long runs.

My invention consists in certain novel features of construction of the means 20 through which the carbon is gripped to lift it in springing the arc and the means through which the electro-magnet exerts its pull upon the carbon lifting means, all of which will be hereinafter fully described and 25 particularly pointed out.

In the accompanying drawings, Figures 1 and 2 are elevations of the improved lamp, Fig. 1 showing the lamp as seen from the left of Fig. 2, and Fig. 2 showing the lamp as 30 seen from the right of Fig. 1. Fig. 3 is a detail plan view of the lifting lever. Fig. 4 is a detail plan view of the clutch through which the carbon is gripped.

1 represents a post projecting from any 35 suitable base, and 2 is a socket loosely fitting said post, so as to be not only vertically adjustable thereon, but to permit slight angular adjustment of the lamp.

3 represents a set screw for fixing the vertical adjustment and 4 represents a lifting screw passing through the arm 2 and locked to its adjustment by a jam-nut 4^a so as to determine the angular position of the lamp on its base. The post and socket are circular in cross section and thus admit of adjustment by limited rotation.

The angular adjustment of the lamp upon its base is obtained by rotating the socket 2 on the post 1. At the same time the vertical adjustment of the lamp may be secured by raising or lowering the socket upon the post. For this purpose the lifting screw 4 is adapted to adjust the vertical height. The desired adjustment having been secured, the

set screw 3 is screwed in tight against the 55 post 1 to maintain the adjustment.

5 represents a standard or upright deflected at its upper end to provide a horizontal arm 6.

7 represents a lower horizontal arm projecting from the upright 5. 60

8 and 9 are the electrodes which are supported respectively from the upper arm 6 and the lower arm 7. The upper electrode is of carbon; the lower electrode is of metal. By making the upper electrode of carbon, I retain all the advantages of a carbon electrode lamp. By making the lower electrode of metal (preferably copper), I avoid the disadvantages due to wearing away of the lower electrode and lowering of the position of the 70 arc; also do away with spitting at times or fluctuation in light; and the lamp is adapted for the long runs without adjustment.

The use of means for varying the lengths of the arms 6 and 7 for the purpose of bringing the arc X into coincidence with the focal center of a reflector in connection with which the lamp is to be used, is made unnecessary since such adjustment may be accomplished roughly by shifting the post 1 or the base. 75

The upper arm 6 carries a T-head 10 upon which is mounted the vertical slide track 11 for the upper carbon. The upper carbon is mounted upon slide track 11 through the medium of a clip 12; such for instance, as disclosed in expired Letters Patent No. 422,446, granted March 4th, 1890. This clip receives the upper end of the carbon, as shown in Fig. 2 and is provided with embracing lugs 13 which permit the clip to 85 slide downward on the track 11 as the carbon 8 is consumed.

14 represents the solenoid, whose winding is in series with the lamp circuit and whose core or armature 15 is connected with rod 16 95 which connects at 17 with the lever 18, fulcrumed at 19 and engaging at 20 with the lifting rod 21 for the carbon.

Rod 21 connects at 22 with a clutch 23. Clutch 23 has an opening through which the 100 carbon passes, of such dimension that when the clutch is normal to the axis of the carbon, the carbon will gravitate through the clutch until arrested by contact with the lower carbon, but when the clutch is raised from a 105 point eccentric to the carbon, the clutch will bind upon the carbon and establish lifting connection with it.

24 represents a guide for the carbon 8 which also serves as a rest for the clutch 23 to bring the clutch into position transverse to the carbon for the purpose explained. 5 While the point 22 of connection between the rod 21 and the clutch 23 is eccentric to the carbon, and therefore has a tendency to bind the clutch upon the carbon when the rod 21 lifts, I prefer to provide additional 10 canting means to insure the gripping effect and for this purpose I employ the canting rod 25 which connects with an extension of the clutch 23 at a point more remote from the carbon than the connection 22 and this rod 15 25 is engaged at its upper end 27 by a lifting spring 28 having fixed abutment 29 on the rod 21, so that there is a constant tendency of the spring 28 to raise the rod 25 relatively to the lifting rod 21 and cause the grip to 20 clutch. The upper end of rod 25 is preferably guided upon the rod 21 and for this purpose and for the convenient forming of the upper movable abutment for spring 28, said 25 upper end of rod 25 is bent inward and fashioned as shown to provide an eye through which rod 21 passes.

It will be understood that the lamp, as thus far described, operates on the well known principle of having the carbons separated by the pull of the solenoid 14 on its core 15 until the weakening of the current incident to the swinging of the arc, establishes a balance between the parts; the weakening of the pull due to the wearing away of 35 the upper carbon and the enlargement of the space, permitting the carbon to drop with its clutch until the latter engages the rest 24 when the clutch is released, the carbon slides downward to make a new contact with the 40 lower carbon and the circuit is again established to repeat the operation. The spring 28 for raising the canting rod 25 is of course selected with relation to the weight of the parts imposed upon the point of the clutch 45 23 as it contacts with the rest 24, so as to permit the clutch to turn upon its pivot 22 in opposition to said spring.

In order to steady the movement of the lever under the pull of the solenoid and the inertia of the loads imposed upon the respective ends of the lever 18, the pull of the solenoid is opposed by a spring 30 adjustably suspended at 31 and connected at 32 with the yoke 33 which has slot and pin bearings 34 50 on the bracket 35 projecting from the upright 5 and connects at 36 with the core 15; while the bracket 35 carries the plunger 37 of the dash-pot 38, the cylindrical member of which is connected at 39 with the lower arm 60 of the yoke 33. Thus, the solenoid is not only opposed by the constant pull of the spring 30, which may be regulated at will by adjusting its upper end, but sudden movements of the solenoid are prevented by the 65 dash-pot. Yoke 33 serves also as the means

through which to connect the rod 16 with the core 15, such connection being shown at 40. The spring 30 also balances the weight of the parts sustained by the rod 16 and since its resistance increases with its distention, its 70 steadyng effect, after the carbons are separated, is exerted to the best advantage.

Having thus described my invention, what I claim and desire to secure by Letters Patent is:

1. In a lifting device for arc lamps, the combination with an electrically operated lifting rod; of a clutch pivotally connected intermediately of its ends to one end of said lifting rod; a canting lever pivotally connected at one end of the clutch and provided at its other end with a bent portion adapted to slidably engage the lifting rod; a collar rigidly secured to said lifting rod; and a spring mounted on the lifting rod between the collar and the bent portion of said canting lever whereby when the lifting rod is operated, the clutch is oscillated upon said lifting rod. 80 85

2. In an arc lamp the combination with the standard provided with an upper and a lower horizontal arm; of a lever pivotally mounted intermediately of its ends, upon the upper arm of said standard; a clutch-lifting rod pivotally connected to one end of said lever; a rod depending by one end from the other end of said lever; a yoke connected with the other end of said depending lever; a guide upon which said yoke slides a dash pot comprising two members one of which is fixed to the standard and the other of which is connected to the yoke, carried on said yoke and having its axis in the same vertical plane as the depending rod; a solenoid rigidly secured to said standard; an armature depending from the yoke and connected with said 100 solenoid; and a spring for supporting the yoke and the parts mounted on the yoke. 105

3. In an electric headlight, the combination with the standard; of a lever pivoted at its middle point upon said standard; a clutch-lifting rod suspended from one end of said lever; an operating rod depending from the other end of said lever; a solenoid rigidly mounted on said standard; a bracket mounted upon the standard above the solenoid; a yoke slidably mounted upon said bracket; an armature for said solenoid, depending from said yoke; a spring secured to a part rigid with the standard, said spring acting to support the weight of the yoke and those parts supported by said yoke; a piston mounted on said bracket; and a dash-pot mounted on the yoke and fitting over said piston, said dash-pot and piston acting to regulate the movement of the yoke under the action of the 115 120 125 spring and the solenoid.

4. In an electric headlight, the combination with a standard having an upper and a lower arm; a solenoid rigidly secured to said standard adjacent to said lower arm; a 130

spring depending from a part rigid with said standard and adjacent to said upper arm; a bracket rigidly mounted on said standard intermediately of said upper and lower arms; a yoke slidably mounted upon said bracket and suspended from said spring; an armature within said solenoid, said armature being suspended from said yoke; a piston carried by said bracket; a dash-pot mounted upon 10 said yoke and adapted to interact with said

piston to regulate the movement of said yoke; and a rod for actuating the carbon-clutching mechanism.

The foregoing specification signed at Houston, Texas this twenty third day of July, 15 1907.

BENJAMIN B. LACY.
